FRONT PANEL FOR A VENDING MACHINE

David S. Zipp, Los Angeles, Calif.
(14649 Arminta St., Van Nuys, Calif. 91402)

Filed Oct. 26, 1970, Ser. No. 25,664

Term of patent 14 years

Int. Cl. D9—99

U.S. Cl. D52—3

FIG. 1 is a front perspective view of a front panel for a vending machine, showing my new design;

FIG. 2 is an enlarged front elevational view thereof;

FIG. 3 is a left side elevational view thereof; and

FIG. 4 is a right side elevational view thereof.

I claim:

The ornamental design for a front panel for a vending machine, substantially as shown and described.
